UNITED STATES PATENT OFFICE.

HENRY SORG, OF ROCHESTER, NEW YORK.

STENCIL APPARATUS.

SPECIFICATION forming part of Letters Patent No. 495,604, dated April 18, 1893.

Application filed June 6, 1892. Serial No. 435,768. (No model.)

To all whom it may concern:

Be it known that I, HENRY SORG, of Rochester, in the county of Monroe and State of New York, have invented a certain new and useful Improvement in Stencil Apparatus; and I do hereby declare that the following is a full, clear, and exact description of the same, reference being had to the drawings accompanying this specification.

10 My improvement relates to stenciling apparatus and consists in the construction and arrangement of parts hereinbefore described and claimed.

In the drawing—Figure 1 is a plan view of 15 the apparatus. Fig. 2 is a longitudinal vertical section in line $\alpha\alpha$ of Fig. 1. Fig. 3 is a plan view of one end of the flexible stencil ribbon and a portion of the guide with which it connects. Fig. 4 is a cross section of the 20 ribbon and an elevation of the inking roller.

A indicates the frame, consisting of two side bars $a a$ and a rear cross bar b .

c is a handle by which the device is held and operated.

25 My improvement is as follows:

B and B' are two rollers, one in front of another, mounted on fixed shafts $d d$ between the sides $a a$ of the frame.

20 ff are spiral springs resting inside the rollers and around the shafts, one end of each being attached to the roller and the other to the shaft. By this means spring action is imparted to the roller sufficient to wind up the stencil ribbon.

35 C C are the stencil ribbons or bands, one for each roller. They are attached to the rollers and wound up thereon. They are cut with a series of letters, figures, or other desired characters, and when the device is in use are brought under the inking roller by simply drawing the

40 ribbon outward against the tension of the spring roller. I do not limit my invention to any particular number of spring rollers and ribbons. For ordinary purposes a single roller and ribbon are sufficient. Where two ribbons are used one preferably has letters and the other figures.

45 D is a guide, consisting of a wire loop or stirrup fastened at one end to the frame, the other end extending forward angularly as shown, and the free ends of the ribbons running through the same. The ends of the rib-

bons have rods $g g$, which project sufficiently beyond the sides of the guides to prevent the ribbons from being drawn back free of the 55 guides. This is shown in Fig. 3. On the back of the guide are stops $h h$, to prevent the ribbons from slipping down out of place when not in use. On the edges of the ribbons are narrow flexible strips $k k$, of rubber or other 60 suitable material, which will wind with the ribbons, said strips serving as dams to prevent the ink from flowing off at the sides. Small pins $l l$ may also be placed at the sides, opposite the characters on the ribbon, to indicate 65 their position when drawn out for use.

E is the ink well, mounted in a suitable position on the frame, its top having a filling cap m , and its bottom a slot or opening through which the ink can pass. G is a transferring 70 roller under the well, and H is the inking roller for applying ink to the ribbon. The two rollers are always in contact, and are geared together by spur gears $n n$ at one end. The bottom of the ink well is protected by a felt or 75 other packing o , which prevents leakage. The felt may be dispensed with.

In use the apparatus is placed over the surface to be marked and the ribbon is drawn out till the desired letter rests under the inking 80 roller. The latter is then rolled over it till the print is made. The apparatus is then shifted sideways to the position for the second letter, the ribbon is drawn out to bring the second letter under the inking roller, and this process 85 is repeated till the desired word is printed. When the ribbon is released the spring roller draws it back to place. The ribbon is preferably made of thin and flexible sheet metal, but may be made of any other suitable material. 90 The inking roller also has preferably a composition similar to that used on printers' rollers, but any suitable substitute may be used.

Having described my invention, I do not 95 claim a set of rollers with an endless stencil band passing between them.

What I claim as new, and desire to secure by Letters Patent, is—

1. In a stencil apparatus, the combination, 100 with the frame A, of the inking apparatus consisting of the inking roller H, transferring roller G and well E, mounted on the rear of the frame, the spring roller B, mounted on the

front of the frame, and the stencil ribbon C attached to the roller and winding thereon by its spring action, as shown and described and for the purpose specified.

- 5 2. In a stencil apparatus, the combination, with the inking apparatus consisting of the ink roller H, transferring roller G and well E, and with the stencil apparatus consisting of the spring roller B and ribbon C, of the guide 10 D, consisting of a loop, arranged angularly

between said parts and provided with a stop h for holding the free end of the ribbon, as herein shown and described.

In witness whereof I have hereunto signed my name in the presence of two subscribing 15 witnesses.

HENRY SORG.
